William A. Hoover, Mount Lebanon, Pa.

Application July 10, 1941, Serial No. 401,840

9 Claims. (Cl. 302—44)

This invention relates to a powder distributor or spray gun, and more particularly to a distributor which is adapted to be mounted on the delivery of a printing press and actuated by mechanism forming a part of the press for intermittently discharging powder into a passage and conveying the powder by air pressure from a discharge pipe onto a freshly printed sheet which has been moved to a position on the delivery of the press.

More particularly, it is an aim of the invention to provide a novel distributor for powder of simple construction and forming a unit which can be readily and removably mounted on the delivery of a press and which is provided with an operator attached to the press and arranged to be engaged by a movable element thereof to intermittently agitate the powder container of the distributor to cause a quantity of powder to be discharged into the passage, and for also intermittently opening a valve of said passage to allow air under pressure to be admitted thereto for conveying the powder thus discharged from the container through the passage.

More particularly, it is an aim of the invention to provide a distributor so constructed that conventional powder containing cans can be mounted thereon in an inverted position and which is provided with a reciprocating rod, forming the agitator, and which is actuated intermittently to strike the apertured cap of the powder can for agitating the can to dispense a quantity of powder therefrom.

Still a further aim of the invention is to provide means for adjustably positioning the agitator rod to cause the rod, when reciprocated, to strike the discharge end of the powder container with varying amounts of force to vary the amount of powder that will be dispensed from the container.

Another aim of the invention is to provide a powder distributor having a blower driven by an electric motor for supplying air for conveying the powder, said motor being provided with a shutoff switch, and a lever for shutting off the switch and for locking the other parts of the distributor for holding the valve in a closed position and for preventing operation of the agitator.

Other objects and advantages of the invention will hereinafter become more fully apparent from the following description of the drawings, which illustrate a preferred embodiment of the invention, and wherein:

Figure 1 is a side elevational view showing the

distributor mounted on the delivery of a conventional printing press.

Figure 2 is an enlarged fragmentary side elevational view looking toward the opposite side of the distributor.

Figure 3 is a fragmentary top plan view of the distributor with the powder can removed therefrom.

Figure 4 is an enlarged vertical sectional view, partly in elevation, taken substantially along the plane of the line 4—4 of Figure 3.

Figure 5 is an enlarged horizontal sectional view taken substantially along the plane of the line 5—5 of Figure 2.

Figure 6 is an enlarged transverse vertical sectional view taken substantially along the plane of the line 6—6 of Figure 2.

Figure 7 is a side elevational view, partly in section, of the automatic operator which is adapted to be actuated by a conventional part of a printing press for intermittently actuating the distributor or spray gun.

Figure 8 is a fragmentary plan view of the dispensing end of the powder can.

Figure 9 is a similar view of the dispensing end of another powder can.

Figure 10 is a fragmentary vertical sectional view, partly in elevation of the means for detachably retaining a powder can in an inverted position on the distributor, and

Figure 11 is a horizontal sectional view taken substantially along the plane of the line 11—11 of Figure 2.

Referring more particularly to the drawings, wherein like reference characters designate like or corresponding parts throughout the different views, 11 designates generally a portion of the delivery of a conventional printing press which is provided with a table 12 to receive freshly printed sheets 13, as they are discharged from the press and stacked on the table or support 12 of the delivery 11.

The powder distributor or spray gun, designated generally 14 includes a head portion, designated 15 having a lateral extension 16 which is provided with a perpendicular bore 17. A stud 18, as best seen in Figure 1, projects upwardly from the delivery 11 and is adapted to be engaged by the lower end of a tubular standard 19 which fits thereover and which is provided with a set screw 20 for detachably securing the standard 19 to the stud 18. The upper end of the standard 19 extends into the bore 17 of the portion 16, which portion is provided with a set screw 21 for securing the head 15 thereon. The

standard 19 forms the support for mounting the distributor or spray gun 14 on the delivery 11 and thereabove.

The head 15 includes a main portion 22 which is provided with a removable top plate 23 which extends from one end to adjacent the opposite end thereof and which is detachably mounted by fastenings 24. Portion 22 is provided with a horizontal bore 25 which extends longitudinally therethrough and the plate 23 is provided with an opening 26 which opens into the bore 25, intermediate of its ends, and which is adapted to receive a cap or discharge end 27 of a powder container or can 28 which is mounted on the portion 22 and in an inverted position. Plate 23 is provided with a threaded opening 29 for receiving the lower threaded end of a rod 30 which projects upwardly from the head 15 and which is disposed adjacent to a portion of the side wall of the can 28. As seen in Figures 1 and 10, a lug 31 is provided with an opening 32 which slidably engages the rod 30 and a set screw 33 for adjustably securing the lug 31 to the rod 30. Lug 31 is provided, at one end thereof, with a depending extension 34 which is adapted to engage the inner side of the rim 35 of the bottom of the can 28 to provide means for effectively holding the can in an inverted position and with its cap 27 in engagement with the opening 26. Cap 27 is provided with apertures 36 and, depending upon the amount of powder to be dispensed from the container 28, cap 27 may be provided with four apertures 36, as seen in Figure 8, or a similar cap 27 having only two apertures 36 could be used. Likewise, the caps 27 could have one, three, or more than four apertures 36 if desired, and said apertures could be made of various sizes.

A pipe 37 has one end removably mounted in the discharge end 38 of the bore 25 and said end of the pipe 37 is secured in the discharge end 38 by means of a set screw 39, as seen in Figure 3, which is mounted in the portion 22. An elbow 40 is connected at one end thereof to the opposite end of the pipe 37 and has its opposite end directed and opening downwardly and above the stacked sheets 13, as seen in Figure 1.

The head 15 also includes a substantially flat horizontally disposed plate 41 through which project a plurality of fastenings 42 which are attached to the base 43 of an electric motor 44 which is supported thereby in a depending position beneath the plate 41. The electric motor 44, which is of conventional construction, is connected by means of wiring 45 to a source of electric current, not shown, and said wiring is also provided with a switch 46 adapted to be closed and opened for energizing and deenergizing, respectively, the motor 44. A blower 47 includes a casing 48 which is formed of detachable sides 49 and 50 connected by nut and bolt fastenings 51 and an intermediate portion 52 which is preferably fixedly connected to the inner side 49. The plate 41, as seen in Figure 1, is provided with a depending flange portion 53, as seen in Figure 1, to which casing 48 is connected by certain of its fastenings 51.

A propeller, designated generally 54, is rotatably mounted in the casing 48. The propeller 54 includes an outer disk 55 having a hub portion 56 which is keyed to the driven shaft 57 of the motor 44, an inner ring 58, which is spaced from the outer portion of the outer disk 55, and a plurality of radially projecting vanes 59 which are disposed in circumferentially spaced relationship relatively to one another and which are con-

nected along their side edges to the disk 55 and the ring 58. The vanes 59, as best seen in Figure 4, are all curved similarly in a clockwise direction from their inner to their outer ends.

As seen in Figure 4, casing 48 is provided with an upwardly opening portion 60 formed by portions of the side walls 49 and 50 and by the ends of the casing portion 52. The side 49 is provided with a central opening 61 which opens toward the motor 44 and which forms the inlet of the blower casing 48. The outlet 60 communicates with the inner, inlet end 62 of the bore 25 and also is provided with a restricted opening 63 which opens outwardly of the top of the head 15 and beyond the rear end of the plate 23. A shaft 64 is journaled in the walls 49 and 50 and extends through the upper portion of the outlet 60. A valve 65 is keyed to the shaft 64 and is disposed in the outlet 60 and is arranged so that when in a closed position, as seen in Figure 4, it will close the entrance end 62 of the bore 25. When thus positioned, as seen in Figure 4, it will be readily apparent that the valve 65 will cause the air from the blower to pass upwardly and be discharged into the atmosphere through the opening 63. The valve 65 is provided with a lug 66 which projects outwardly from its pivoted end and at substantially a right angle to the plane of the valve. A set screw 67 is mounted in the rear end of the plate 23 and forms a stop to be engaged by the lug 66 to limit the swinging movement of the valve 65 in a counterclockwise direction, as seen in Figure 4, and toward an open position. It will be apparent that the set screw 67 can be adjusted for varying the extent to which the valve 65 can be moved toward an open position, as indicated by the arrow 68.

The head 15 includes a flange 69 which depends from the under part of the portion 22, adjacent the blower casing 48. A plate 70 is provided with an angular end 71 which is attached to the outer side of the flange 69, adjacent its lower end, by means of fastenings 72 for mounting the plate 70 substantially at right angles to the flange 69. A flat bar 73 is attached to the outer side of the flange 69, above the plate 70 by a fastening 74 and is provided with an outwardly projecting free end 75 which is disposed at an oblique angle to the plate 70, as best seen in Figure 6. The plate 70, adjacent its free end, is provided with a threaded opening 76 to which is threaded an externally threaded sleeve 77. The lower portion of the part 22 is provided with a perpendicular bore 78 which is in alignment with the bore of the sleeve 77 for slidably engaging the upper end or stem 79 of an agitator, designated generally 80, which is provided at its lower end with a stem 81 which slidably engages the bore of the sleeve 77. Between the stems 79 and 81, the agitator 80 is provided with an enlargement 82 and an enlargement 83, disposed beneath the enlargement 82 and which is of a greater diameter than the enlargement 82 to form at the top thereof an annular upwardly facing shoulder 84. The upper end of the stem 79 is adapted to engage against the underside of the cap 27 when the agitator 80 is in a raised position, as seen in Figure 4, and when thus positioned the upper end of the enlargement 82 is disposed slightly below the portion 22. An expansion coil spring 85 is mounted on the stem 81 and has one end thereof bearing against the upper end of the sleeve 77 and its opposite end bearing against the underside of the enlargement 83 for normally holding the agitator

80 in a raised position. A nut 86 is carried by the sleeve 71, beneath the plate 70, and it will be readily apparent that the sleeve 71 can be adjusted relatively to the opening 76 for varying the tension on the spring 85 and the nut 86 may be tightened against the underside of the plate 70 to hold the sleeve 71 in adjusted positions.

An L-shaped lever 87, as best seen in Figures 2 and 3, is provided with an enlarged inwardly projecting hub portion 88 at its apex through which loosely extends a pivot pin 89. Pivot pin 89 extends into the side of the head portion 22, adjacent the discharge end 38, and is secured therein by means of a set screw 90 for pivotally mounting the lever 87 on the side of the portion 22, opposite to the portion 15. The lever 87 is provided with a longer substantially horizontally disposed arm 91 which extends toward the blower 47 and a shorter, depending arm 92 which is disposed substantially at a right angle to the arm 91. A stop 93 projects outwardly from the portion 22 to engage the underside of the arm 91 to limit the swinging movement of the lever 87 in a clockwise direction, as seen in Figure 2, and a similar stop 94 projects outwardly from the portion 22 and is disposed to engage the upper side of the arm 91 to limit its swinging movement in a counterclockwise direction.

Referring to Figure 5, the depending arm 92 is provided adjacent its lower end with an inwardly projecting flange 95 and a forwardly projecting lug 96 which is provided with a recess 97 on its inner side. A lever 98 is pivotally connected at one end thereof by means of a pivot pin 99 to the upper side of the flange 95 for pivotally mounting the lever 94 for swinging movement in a horizontal plane. The lever 98 is a substantially flat bar, as seen in Figure 6, and is provided with notches 100 in one longitudinal edge thereof and adjacent its pivoted end, for seating one end of an expansion coil spring 101, the opposite end of which is seated in the recess 97 for urging the lever 98 to swing toward the portion 22. As seen in Figures 5 and 6, the free end of the lever 98 is disposed to engage against the inclined plate portion 15 which forms a cam surface and its intermediate portion adapted to rest on the shoulder 84.

As seen in Figure 2, one end of the shaft 64 projects outwardly through the outer side 50 of the casing 43 and a cam member 102 is keyed thereto by means of a set screw 103. The upward swinging movement of the cam member 102 in a clockwise direction, as seen in Figure 2, is limited by a stop pin 104 which projects from a portion of head 15. The under, rounded side of the cam 102 rests on the upper side of the arm 91, adjacent its free end. A leaf spring 105 is attached to the upper side of the arm 91 at one end thereof by a fastening 106 and projects therefrom toward the free end of the arm 91. The free end of the leaf spring 105 engages the upper side of the cam 102, for a purpose which will hereinafter be described.

The plate 76 is provided at its outer end with an integral perpendicularly disposed clamp 107 in which is clamped one end of a flexible conduit 108 through which extends a flexible shaft 109. One end of the shaft 109 projects outwardly from the end of the conduit 108 which is secured in the clamp 107 and said end is provided with a head 110 which is pivotally connected to the arm 91, intermediate of the ends thereof. An expansion coil spring 111 is mounted on said exposed end of the shaft 109 and has its upper end

bearing against the underside of the head 110, and its lower end bearing against the upper end of the clamp 107 for urging the lever arm 91 upwardly to thereby hold the parts 98 and 102 in the positions, as seen in Figure 2, in which positions the valve 65 is held in a closed position, as seen in Figure 4, by the cam 102 and the agitator 80 is held in an elevated position, as seen in Figure 4 by its spring 85.

Referring to Figure 7, the opposite end of the conduit 108 is secured in a clamp 112 which forms a part of the plate 113 which is adapted to be fastened to a part of the printing press, not shown. An angular lever 114 is pivotally mounted at its apex by means of a pin 115 on the plate 113. One end of the lever 114 is provided with a clamp portion 116. The opposite end of the flexible shaft 109 projects through and beyond the last mentioned end of the conduit 108 and is clamped to the lever 114 by the portion 116. A contractile coil spring 117, which is connected at one end to the plate 113 and at its opposite end to the lever 114, urges the lever 114 to swing in a direction for moving the flexible shaft 109, at its last mentioned end, inwardly of or toward the conduit 108. A roller 118 is journaled on the opposite end of the lever 114 and is disposed to be engaged by an element 119, forming a conventional part of the printing press and which makes one revolution each time that a sheet 13 is discharged onto the table 12. The roller 118 is normally held by the spring 117 in the path of movement of the element 119 to be engaged thereby at each revolution thereof for rocking the lever 114 for moving the last mentioned end of the shaft 109 outwardly of the conduit 108, and it will be readily apparent that after the roller 118 moves out of engagement with the element 119 the spring 117 will return the parts to the positions, as seen in Figure 7.

The switch 46 is supported by a bracket 120, as best seen in Figure 2, which is attached to the plate 41 by fastenings 121 and which projects outwardly therefrom. The switch 46 is provided with a throw arm or operator 122 which projects upwardly from the bracket 120. A lever 123 is pivotally mounted intermediate of its ends on the plate 41 by means of a pin or bolt 124. A link 125 is pivotally connected at one end thereof at 126 to the lever 123, adjacent its pivot 124. The link 125 is provided with an opening 127, adjacent its free end, which loosely engages over the operator 122. A plate 128 is attached to and projects laterally from the forward end of the lever 123 to form a stop.

In Figures 2 and 3, the lever 123, which controls the operation of the spray gun or distributor 14 is shown in a released position and in which position the switch 46 is closed. By swinging the lever 123 in a clockwise direction, as seen in Figure 3, the link 125 will be moved to the left to open the switch 46 to deenergize the motor 44, and the stop 128 will be moved into a position between the cam 102 and the arm 91 to prevent the cam 102 from swinging downwardly for opening the valve 65 and to prevent the lever 87 from swinging upwardly to its fully raised position, as seen in Figure 2.

With the parts in the positions, as seen in the drawings, it will be readily apparent that as the element 119 engages the roller 118 to rock the lever 114, as previously described, a pull will be exerted on the flexible shaft 109 for swinging the lever 87 in a clockwise direction, as seen in Figure 2. This must of course occur while the lever 123 is in its position of Figure 3 and therefore

while the motor 44 is in operation. Referring to Figures 5 and 6, when the lever 87 is thus moved in a clockwise direction, the lever 98 will be swung downwardly and as it is engaging the shoulder 84 it will draw the agitator 80 downwardly. The free end of the lever 98 by engagement with the cam surface 75 will be swung outwardly as it moves downwardly against the action of the spring 101 so that after the lever 98 has moved a predetermined distance it will swing on its pivot 99 sufficiently to move out of engagement with the shoulder 84 to allow the spring 85, which has thus been compressed, to drive the agitator 80 upwardly to cause the stem 79 to strike the cap 27. The impact of the blow of the stem 79 will agitate the container 28 to cause a quantity of the powder 129 contained in the container 28 to be dispensed through the apertures 36 and into the bore 25. It will be readily obvious that, as previously explained, the amount of powder dispensed by the agitator 80 can be varied by adjusting the sleeve 77 to vary the force with which the stem 79 strikes the cap 27. Also, the amount of powder to be dispensed can be controlled by providing the cap 27 with more or less apertures 36, as previously explained, and as illustrated in Figures 8 and 9. At the same time that the agitator 80 is being moved downwardly, the lever arm 91 is moving downwardly and away from the cam 102 so that its spring 105 can swing the cam 102 in a counterclockwise direction, as seen in Figure 2, for swinging the gate valve 65 in the same direction for moving it to an open position to allow the air from the propeller of the blower 47, which is revolving in a clockwise direction, as seen in Figure 4, to be admitted to the bore 25 so that when the powder is dispensed into the bore 25 it will be conveyed by the air through the bore 25, through the pipe 37 outwardly and downwardly through the elbow 40 to be discharged onto the uppermost freshly printed sheet 13 which has just been stacked on the table or support 12 in a conventional manner by the printing press.

After the element 119 has moved out of engagement with the roller 118, the springs 117 and 111 will slide the flexible shaft 109 in a direction toward the lever 87 to allow the lever to swing in a counterclockwise direction, as seen in Figure 2, by the action of the spring 111 back to its original position. This will cause the cam 102, by engagement with the lever arm 91, to be turned in a clockwise direction for similarly turning the valve 65 to return said valve to a closed position, as seen in Figure 4, so that the air from the blower 47 cannot be admitted to the bore 25 but will be discharged into the atmosphere through the opening 63. At the same time, the lever 98 will be swung upwardly and as it moves upwardly its inner edge will slidably engage a portion of the periphery of the enlargement 83. As the lever 98 approaches its uppermost position it will move to the position above the level of the upper end of the enlargement 83 at which time its spring 101 will swing the lever 98 inwardly to return it to the position, as seen in Figures 5 and 6. In this position, lever 98 will be resting on or disposed above the shoulder 84 for drawing the agitator 80 downwardly the next time that the element 119 contacts the roller 118.

It will thus be apparent that the distributor or spray gun 14 is operated automatically for spraying powder on each freshly printed sheet 13 after it is conveyed by the printing press to the delivery 11, and that the operation of the spray gun or distributor 14 is automatic and intermittent.

Various modifications and changes are contemplated and may obviously be resorted to, provided they fall within the spirit and scope of the invention as hereinafter defined by the appended claims, as only a preferred embodiment of the invention has been disclosed.

I claim as my invention:

1. A powder distributor comprising a head having a bore extending horizontally therethrough and adapted to be connected to a source of air supply, said head being provided with an opening adapted to receive the apertured cap of a powder container, said opening communicating with the upper portion of the bore and opening outwardly of the top of the head, the powder container being adapted to be supported in an inverted position on the head, a rod having a restricted stem at its upper end slidably mounted perpendicularly in said head and extending transversely through said bore, the free end of said stem engaging against said apertured cap, spring means for urging said rod upwardly, and means for periodically drawing the rod downwardly and releasing the rod to allow the spring means to project the rod upwardly to cause the stem to strike the apertured cap for agitating the container for dispensing the powder into said bore.

2. A distributor as in claim 1, said means comprising a pivotally mounted lever, said rod being provided with an upwardly facing shoulder near its lower end, a spring for urging the free end of said lever to swing toward said rod to position a portion of the lever above said shoulder, a cam element mounted on said head and disposed to be engaged by the free end of said lever, and means for swinging said lever downwardly to cause it to engage said shoulder for drawing the rod downwardly, the free end of said lever engaging said cam during its downward motion and being swung thereby in a direction away from the rod, as said lever is swung downwardly, for moving the lever out of engagement with the shoulder when the parts have reached a certain position on their downward movement.

3. A distributor as in claim 1, comprising a valve mounted at the inlet end of said bore and connected to said means to be moved to an open position when said rod is drawn downwardly.

4. A distributor as in claim 1, comprising a blower provided with a casing having a discharge opening connected to the inlet end of said bore and providing the source of air supply for the distributor.

5. A powder distributor comprising a head having a bore extending therethrough and provided with means for supporting a powder container in an inverted position on the head and with its discharge end opening into said bore, a blower connected to the inlet end of said bore, a valve for controlling the passage of the air to the bore, a reciprocating rod slidably mounted in said head and extending upwardly through the bore for engaging the outlet end of said container, spring means for urging said rod upwardly, and intermittently actuated means for moving said rod downwardly and for simultaneously opening said valve.

6. A distributor as in claim 5, comprising an electric motor for driving the blower, said motor being provided with a shutoff switch, a control lever pivotally mounted on the distributor and provided with a link connected to said switch for opening or closing the switch when the control lever is actuated, and a stop element pro-

jecting from one end of said control lever and arranged to engage said means, when the switch is in an off position, for preventing said rod and valve from being actuated.

7. A distributor as in claim 5, comprising a conduit connected at one end to the outlet end of said bore and projecting outwardly from the head, said conduit being provided with an opposite downturned discharge end from which the air and powder is discharged.

8. A distributor as in claim 5, said means including a pivotally mounted arm, a rocker arm remotely disposed relatively to the distributor and adapted to be disposed in the path of and to be engaged by a moving part of a printing 15 press for intermittently actuating said rocker

arm, said arm and rocker arm being provided with connecting means for moving said arm downwardly, when said rocker arm is actuated for actuating said rod and for opening the valve, and spring means for returning said rod to its normal position and for closing said valve.

9. A distributor as in claim 5, comprising a sleeve member in which said rod is slidably mounted, said sleeve member being adjustable and movable toward and away from said head for adjustably positioning the rod relatively to the discharge end of said container for varying the force with which said rod will strike the container.

WILLIAM A. HOOVER.
